UNITED STATES PATENT OFFICE.

MORRIS U. BERNHEIM, OF CINCINNATI, OHIO, ASSIGNOR TO THE ALVEY-FERGUSON COMPANY, OF OAKLEY, CINCINNATI, OHIO, A CORPORATION OF OHIO.

SPIRAL CONVEYER.

1,250,778.

Specification of Letters Patent. Patented Dec. 18, 1917.

Continuation in part of application Serial No. 696,918, filed May 18, 1912. This application filed January 27, 1915. Serial No. 4,593.

To all whom it may concern:

Be it known that I, MORRIS U. BERNHEIM, a citizen of the United States, residing at Cincinnati, in the county of Hamilton and State of Ohio, have invented certain new and useful Improvements in Spiral Conveyers, of which the following is a specification.

This invention relates to spiral conveyers of the type embodied in my application Serial No. 696,918 which matured into Patent No. 1,129,781 granted Jan. 27, 1915, the present application being a continuation in part of the aforesaid application No. 698,918 differing therefrom only in the inclusion of a certain locking mechanism hereinafter described.

In the type of conveyers referred to there are three ways extending spirally around an internal column or other suitable supporting member. Two of these ways (hereinafter designated "first spiral" and "second spiral" respectively) are arranged at one side of what is arbitrarily termed a junction place and the other way (hereinafter termed "third spiral") is arranged at the other side of said junction place and at the junction there is an opening and a pivotally adjustable member adapted to bridge the opening and whose position controls communication of the "third spiral" with either of the other spirals, at will.

The particular form constituting the present invention includes as one of its most important features a correlation of parts such that the bridging member moves in an upward or downward direction in its adjustments between the first and second spirals. More particularly, one of the most important features of the present embodiment is a correlation of spirals such that the terminals of the first and second spirals adjacent to the bridging member are arranged in different horizontal planes and are separated from the end of the third spiral by spaces which are alternately opened and closed by a bridging member arranged to have rising and falling movement pivotally, there being no connection over which the packages pass from the third spiral to either of the other spirals except such as is afforded by the adjustable bridging member itself, the latter being adjust-

able in its entirety instead of being composed of relatively adjustable sections, one of which permanently connects the third spiral with one of the other spirals and the other of which (the adjustable section) is arranged to temporarily, so to speak, connect the third spiral with the remaining spiral.

The features hereinbefore referred to are preferably embodied in a spiral conveyer whose third spiral is arranged in a different vertical plane from that of the first and second spirals and this preferred embodiment of the invention is herein illustrated. I have also illustrated and will hereinafter describe in detail a means by which the bridging member may be adjusted from any one of several floors from which packages may be placed upon the third spiral, the said means being combined with and automatically controlling the operation of a locking mechanism which is arranged to hold the bridging member against displacement from its upper position when a package is passing thereover from the third spiral to the upper one of the remaining spirals.

A conveyer embodying the correlation of parts hereinbefore set forth is herein exemplified but it will be understood that the particular embodiment shown is merely intended to be exemplary and that other specifically different embodiments thereof fall within the spirit of the invention and the scope of the subjoined claims.

In the accompanying drawings, wherein like characters of reference denote corresponding parts:

Figure 1 is a form showing the junction of the three spiral ways embodied in a particular form of conveyer exemplifying the present improvements;

Figs. 2, 3 and 4 are detail representations particularly intended to show the locking mechanism for the bridging member including the means by which the locking mechanism is released from said member; Fig. 2 being a section on the line 2-2 of Fig. 3 and Figs. 3 and 4 showing partly in section and partly in elevation the position of the parts when the bridging member is in raised and lowered positions, respectively.

In the particular form of the invention

herein exemplified the internal supporting member is composed of two sections, marked A²⁰ and A²¹ respectively. These sections are offset from each other. Around the section A²⁰ the "first spiral", marked B²⁰, and the "second spiral", marked C²⁰, extend, the said spirals having their upper terminals b²⁰ and c²⁰ in different horizontal planes as shown. The "third spiral", D²⁰, extends around the section A²¹ of the internal supporting member, and its lower terminal, d²⁰, is spaced from the upper terminals of the other spirals. In this space is mounted the pivotally supported bridging member, E²⁰. In the herein exemplified form of the invention each spiral B²⁰, C²⁰ and D²⁰ is a smooth blade but it will be understood that they may be of any construction adapted to cause packages to travel thereover in a spiral path by gravity. The bridging member should be of a type analogous to that of the remaining parts of the ways—and accordingly is here shown as having a smooth surface—that is, free from rollers. It is curved and pitched, corresponding with the curvature and pitch of the spirals.

When the spiral D²⁰ is in a different vertical plane from that of the spirals B²⁰, C²⁰—as shown in the herein exemplified form of the invention—it is preferred to pivot the upper end of the bridging member E²⁰ in proximity to the end of the spiral D²⁰, as shown at 20, its other end being free to swing from the spiral B²⁰ to the spiral C²⁰ as shown by the full and dotted lines respectively.

It will be understood that in practice the spiral D²⁰ may be of any suitable length so as to serve different floors and also that the spirals B²⁰ and C²⁰ may be of any suitable length and serve a number of floors. The conveyer preferably includes an outer casting F²⁰ of suitable kind, having feed and discharge openings at the various floors. This casing incloses the spirals and the central supporting member, being spaced from the internal supporting member sufficiently to receive the spirals and having its inner wall adjacent to the edges of the spirals. The feed and discharge openings are provided in practice with suitable doors. It is not considered to be necessary more particularly to show or to describe the casing herein, as spiral conveyers have hitherto been provided with such casings and, moreover, the casing is not an essential element of the structure. The casing herein shown has an offset part to adapt it to the offset arrangement of the spirals and internal supporting member.

A conveyer embodying the present improvements will be found to be useful in many cases. The ways or spirals B²⁰ and C²⁰ may be employed respectively to carry packages intended to be discharged at dif-

ferent places, or packages of different characters, receiving said packages from the spiral D²⁰, common to all such packages.

It is desirable to provide means whereby the adjustable bridging member E²⁰ may be adjusted from any of the floors which are served by the spiral D²⁰. Any suitable means may be employed. The one illustrated comprises an endless cable whose runs or strands are designated 56 and 57, respectively. This cable extends throughout the length of the spiral D²⁰ and also to a place suitably below the lower terminal of the latter. Its upper end extends over a suitably supported pulley 58, and its lower end under a suitably supported pulley 59. The cable may be operated from any of the floors served by the spiral D²⁰ and its strands 56 and 57 preferably have on each floor buttons marked 60 and 61 respectively, or other suitable means, for convenience in operating them. Obviously, the position of the buttons will indicate the position of the bridging member. A suitable means, indicated at 62, for maintaining tension on the cable, or for taking up slack therein, will preferably be employed in practice, but as such means are commonly used with cables, chains or the like, it is considered to be unnecessary to describe the same in detail herein.

The terminal c²⁰ of the lower spiral C²⁰ is formed with an offset portion which provides a seat c²¹ for the lower end of the bridging member E²⁰ when the latter is arranged to connect the spiral D²⁰ with the spiral C²⁰, this seat forming a desirable means—which, however, may be varied—by which the bridging member is stopped in proper position with relation to the spiral C²⁰ and is held against falling when a package is passing thereover to the spiral C²⁰. Means are also provided for stopping the bridging member in proper position with relation to the spiral B²⁰ and for holding it against falling when a package is passing thereover to the latter spiral. The latter means should be of a nature such that it may be operated to release the bridging member from any of the floors from which the bridging member may be operated. It also should be operable somewhat in advance of the lowering of the bridging member and furthermore, preferably, should be of a nature such that it automatically holds the bridging member when the latter is raised into operative relation with the spiral B²⁰. Means having these characteristics, which I prefer, comprise a latch which includes a casing 70 connected to the end of the bridging member by a pin 71, or other suitable element, the said pin extending through an arcuate slot 72 in the casing F²⁰ and being connected by a flexible support 73 with a rod 57^a which forms a section of the strand 57 of the cable. The latch also includes a

bolt 74 which projects at both ends from the casing 70. The rod 57^a has a member (hereinafter called "bolt actuator") which comprises a conical portion 75 and a cylindrical portion 76. One end of the bolt 74 is pressed yieldably in engagement with the bolt actuator by a spring 77 and its other end engages a detent 78 which is pivoted at 79 to the casing F²⁰.

It will be seen that when the bridging member E²⁰ is in its raised position its lower end is held against movement under the weight of a package passing thereover by the engagement of the bolt 74 with the detent 78. The correlation of the bolt and bolt actuator in this position of the parts is shown in Fig. 3. When it is desired to lower the bridging member to connect the spiral D²⁰ to the spiral C²⁰, the cable is operated in a direction which moves the strand 57 downward. This movement of the strand 57 carries the cylindrical portion 76 of the bolt actuator out of engagement with the bolt 74 and allows the spring 77 to disengage the bolt from the detent. The bridging member now falls to an extent determined by the slack which has been given the flexible member 73 in the downward movement of the strand 57 and when this slack is taken up by the falling of the bridging member the latter may be lowered quietly to its seat by further downward movement of the strand 57. The correlation of the bolt actuator and bolt when the bridging member is in its lowered position, in operative relation with the second spiral, C²⁰, is shown in Fig. 4. In order to raise the bridging member into operative relation with the first spiral, B²⁰, movement is given to the cable in a direction which causes the strand 57 to travel upward. This upward travel of the strand 57 raises the bridging member and the bolt actuator together, the bolt near the end of its upward travel engaging the detent and pressing the lower end of the latter backward so as to pass above its hook end. When the bolt, and consequently the bridging member have reached their uppermost position, the bolt being above the plane of the hook end of the detent, this detent moves with its hook end forward, by gravity—or by spring pressure, if desired—and engages under the protruding end of the bolt. The upward movement of the bridging member is limited by the length of the slot 72 and after the bridging element E²⁰ has been raised to its upward limit of movement it may be gradually eased down by the manipulation of the strand 57 to permit the bolt 74 to engage with detent 78 as before set forth.

It will be understood that the spirals B²⁰ and C²⁰ may be employed for "charge packages" and "paid packages" or for packages intended to be discharged at different

places, or for packages of different characters and that these spirals, as well as the spirals D²⁰, may extend through any number of floors in a building.

It also will be noted that the correlation of the spirals and adjustable bridging means in each of the particular embodiments of the invention herein described is such that packages are delivered from the third spiral to the first spiral or second spiral, at will, by the mere adjustment of the bridging means and it will be noted further that the correlation of the parts is such that the delivery of the packages between the third spiral and the other spirals is a direct one, the adjustable switching member in none of the herein exemplified forms of the invention serving to carry the packages to discharge openings in the casing or away from the conveyer, or to other conveying mechanisms.

Again, it will be noted that while the conveyer has been described with reference to the use of the third spiral as a means for feeding packages to the first and second spirals, it will not be a departure from the spirit of the invention to reverse this relative arrangement of the spirals, that is to say, to correlate the parts in either of the embodiments herein exemplified so that packages will be fed by the first and second spirals to the third spiral. It will further be noted that, while the conveyer has been exemplified as extending through the floors of a building, it may be arranged outside of the building. These and other changes in the exemplified construction and arrangement of parts are contemplated to be within the spirit of the invention and the scope of the subjoined claims.

Having now described the invention what I believe to be new and desire to secure by Letters Patent, is:—

1. A conveyer comprising a first spiral way and a second spiral way disposed at a common portion of the conveyer and having their corresponding terminals in different horizontal planes, a third spiral way arranged at another part of the conveyer and having its terminal spaced from said terminals of the first and second ways, and an adjustable member for bridging the space between the third spiral way and either of the other spiral ways, at will, said member being pivoted at one end in proximity to the terminal of the third way and being arranged so that its other end may be operatively related to the terminals of the other ways, alternately.

2. A conveyer comprising a first spiral way and a second spiral way arranged at a common portion of the conveyer, a third spiral way disposed at a different portion of the conveyer, with its vertical axis in a different vertical plane from the vertical

axes of the first and second ways, and a member adapted to connect the third way with either of the other ways, said member having one of its ends pivoted adjacent to the third way and being movable from its said end to substantially aline its other end with either of the other ways.

3. A conveyer comprising an internal supporting means having a plurality of sections arranged at different levels and in different vertical planes, a plurality of ways extending spirally about one of said sections, a way extending spirally about the other section with a space between its ends and the ends of the first-mentioned ways, and a bridging member one of whose ends is pivoted in proximity to said separate way and the other of whose ends is movable into substantial alinement from one to the other of the first-mentioned ways.

4. A conveyer comprising a first spiral way and a second spiral way arranged at a common part of the conveyer, a third spiral way arranged at another part of the conveyer and having its terminal spaced from the terminals of the first and second spiral ways, a member bridging the space between the third spiral way and either of the other ways, at will, said member being fulcrumed at one end adjacent to the terminal of the third spiral way, and means operable from different points to adjust the bridging member.

5. A conveyer comprising a first spiral way and a second spiral way arranged at a common portion of the conveyer and having their corresponding terminals in different horizontal planes, a third spiral way arranged at another part of the conveyer and having its terminal spaced from said terminals of the first and second spiral ways, a member bridging the space between the third spiral way and either of the other spiral ways, at will, said member being fulcrumed upon a horizontal axis adjacent to the terminal of the third spiral way, means for adjusting said member and means controlled by the adjusting means for locking it in its raised position.

50 6. In combination, a pair of spiral ways, a third spiral way terminating in spaced relation to the upper ends of the first named ways, a bridging element mounted to move to establish communication between the third spiral way and either of the first named ways, an adjusting means for shifting said bridging element and a lock for holding the bridging element in one of its bridging positions.

60 7. In combination, a pair of spiral ways, a third spiral way terminating in spaced relation to the upper ends of the first named ways, a bridging element mounted to move to establish communication between the third spiral way and either of the first

named ways, a lock mounted to move bodily with the bridging element, a detent with which the lock engages to hold the bridging element in one of its bridging positions, an adjusting means for shifting the bridging element, and means carried by the adjusting means for controlling the lock.

8. In combination, a pair of spiral ways, a third spiral way terminating in spaced relation to the upper ends of the first named ways, a bridging element mounted to move to establish communication between the third spiral way and either of the first named ways, a lock comprising a bolt, carried by the bridging element, a detent for engaging the bolt to hold the bridging element in an elevated position, a spring normally tending to release the bolt, an adjusting means for the bridging element and means controlled by the adjusting means for moving the bolt against the tension of the spring.

9. A conveyer comprising a pair of spiral ways, the helices of one spiral way alternating with the helices of the other and the upper ends of the ways terminating in different horizontal planes, a third spiral way offset laterally from the two first named ways, a bridging element having permanent operative relation to the lower end of the last named way and movable into operative relation with either of the first named ways, means for supporting the bridging element when it is lowered into alinement with one of the first named ways and a releasable locking means for holding the bridging element in an elevated position and in alinement with the other of the first named ways.

10. A conveyer comprising a pair of spiral ways, a third spiral way terminating in spaced relation to the upper ends of the first named spiral ways, a bridging element mounted to move to establish connection between the third spiral way and either of the first named ways, a lock mounted to move bodily with the bridging element and comprising a bolt, a swinging detent with which the bolt engages, spring means normally tending to release the bolt from the detent and manually operable means for forcing the bolt toward the detent against the tension of said spring.

11. A conveyer comprising a plurality of spiral ways having a common vertical axis and having their corresponding ends in different horizontal planes, a separate spiral way whose vertical axis is offset from that of the first mentioned ways, a bridging element one of whose ends is pivoted in proximity to the end of said separate spiral way, said bridging element being movable upon a horizontal axis to aline its other end substantially with the ends of the first mentioned spiral ways, respectively, means arranged outside of and extending longitudinally of the first mentioned spiral ways.

dinally of the conveyer and operable at different places in its length to adjust the bridging element, and means for holding the bridging element in operative relation 5 with the respective first mentioned spiral way.

12. A conveyer comprising a plurality of spiral ways having a common vertical axis and having their corresponding ends in different horizontal planes, a separate spiral way whose vertical axis is offset from that of the first mentioned ways, a bridging element one of whose ends is pivoted in proximity to the end of said separate spiral way, 10 said bridging element being movable upon a horizontal axis to aline its other end substantially with the ends of the first mentioned spiral ways, respectively, a locking member carried by the bridging element, 15 means for adjusting the bridging element, a flexible connection between the adjusting means and locking member, and elements coöperating with the adjusting means and locking member for securing and releasing 20 the bridging element.

13. A conveyer comprising an internal supporting means, a first spiral and a second spiral extending around one part of said means and terminating respectively in different horizontal planes, a third spiral extending around another part of the internal supporting means and having its terminal spaced from the terminals of the first and 30 second spirals, an adjustable member for bridging the space between the third spiral and either of the other spirals, at will, said member being pivoted at one end in proximity to the terminal of the third spiral and being arranged so that its other end may 35 40 be operatively related to the terminals of

the other spirals, alternately, means operable to raise and lower the bridging member, and mechanism for locking the bridging member in its raised position, the locking mechanism including a spring-pressed bolt, 45 a flexible connection between the bolt and the raising and lowering means, a bolt actuator connected with the raising and lowering means, and a detent to engage the bolt when the bridging member is in its raised 50 position.

14. A conveyer comprising an internal supporting means having two portions which are out of line with each other, an outer casing having portions which respectively 55 encircle said portions of the internal supporting member and are spaced therefrom, a pair of ways extending spirally around one of said portions of the internal supporting means, a third way extending spirally 60 around the other of said portions of the internal supporting means, said ways being encircled by the casing, a bridging member to connect the third way with either of the other ways, said member being arranged in 65 the casing and having one of its ends pivoted adjacent to the third way and being movable from its said end to aline its other end with either of the other ways, and means extending from said member and along the 70 outside of the casing for adjusting said member from various points in the height of the conveyer.

In testimony whereof I affix my signature in presence of two witnesses.
